UNITED STATES PATENT OFFICE.

THOMAS LUND, OF BEVERLY, MASSACHUSETTS, ASSIGNOR TO UNITED SHOE MACHINERY COMPANY, OF PATERSON, NEW JERSEY, A CORPORATION OF NEW JERSEY.

DEVICE FOR CUTTING AND ORNAMENTING SHEET MATERIAL.

1,048,842.

Specification of Letters Patent. Patented Dec. 31, 1912.

Application filed May 14, 1909. Serial No. 496,063.

To all whom it may concern:

Be it known that I, THOMAS LUND, a citizen of the United States, residing at Beverly, in the county of Essex and State of Massachusetts, have invented certain Improvements in Devices for Cutting and Ornamenting Sheet Material, of which the following description, in connection with the accompanying drawings, is a specification, like reference characters on the drawings indicating like parts in the several figures.

This invention relates to dies which are used for cutting or dying out pieces of thin sheet material such as upper leather for boots and shoes and contemplates the provision of means whereby such a die may be efficiently used for marking, perforating, embossing or otherwise ornamenting the blanks cut by the die.

More particularly the invention relates to the class of dies used with cutting or clicking presses to cut or die out blanks for the various parts of the uppers of boots and shoes and it is an object of the present invention to provide a die for use with a clicking press which, beside cutting the outline of the blank, shall, when desired, form on or in the blank any desired perforation or ornamentation. An important advantage of such a device is that by its use the operations of cutting and ornamenting, heretofore separately performed, may take place simultaneously, resulting in greater economy of time and uniformity of product.

It is essential in cutting blanks from upper leather that dies having a substantially open, unobstructed center should be employed as it is important that the operator should have an opportunity to inspect critically the blanks about to be cut, in order to locate the die so as to avoid imperfections in the leather.

An important object of the invention, therefore, is to provide a blank ornamenting device which may be used in combination with a die comprising a continuous, open frame having oppositely disposed cutting and pressure receiving edges.

Another object of the invention is to provide a die having a coöperating or supplementary member arranged to cut out from or impress into the blank any desired ornamentation, the construction of such supple-

mentary member permitting the design of the ornamentation to be varied readily according to the taste of the shoe manufacturer.

More specifically this invention contemplates the provision of a die with a supplementary member for the purpose indicated, comprising a plurality of sections, each bearing a device for cutting or impressing on a blank a portion of the useful or ornamental design which it is desired to have appear on the corresponding portion of the finished shoe; together with means for retaining the various sections when once they have been adjusted and arranged to form the proper design. As herein shown, the retaining means itself, together with the punches carried thereby, is capable of adjustment with respect to the cutting edge of the die.

The ornamentation formed on various portions of the upper of a shoe usually is in the nature of a line of perforations extending in proximity to the edge of the blank, the configuration and arrangement of the perforations being varied to suit the style of shoe of which the blank is to form a part. It is difficult to form these perforations cleanly with the hollow punches commonly employed for this work, since if the punches and the cutting bed do not make perfect contact the edges of the perforations are left ragged. To obviate this objection and insure better contact of punch and bed it is customary to insert a sheet of paper between the stock to be perforated and the cutting bed, a step which is objectionable in that it adds to the expense and complicates the process. It is, accordingly, another object of my invention to provide a blank ornamenting attachment for a die by the use of which the ornamentation may be impressed into, instead of cut out from, the blank.

One preferred embodiment of the invention comprises a combined die and blank ornamenting member, said ornamenting member comprising interchangeable sections, some of the latter forming parts of the design and others serving as spacing blocks or sections for determining the proper location of the first mentioned sections. Coöperating with the sections just mentioned and adjustable relative to the

cutting edge of the die, there is provided a retaining bar for said section upon which the latter may be placed as desired and from which they may be removed and others substituted when the design is to be changed. Thus, by combining the various sections upon the retaining bar, different designs may be built up somewhat after the manner type is set in a printer's composing stick.

10 These and other features of this invention however, will be best understood and appreciated from the following description of one embodiment thereof selected for purposes of illustration and shown in the accompanying drawings, in which:

Figure 1 is a perspective view of a die provided with my improved blank ornamenting device, the cutting edge of the die being uppermost; Fig. 2 is a perspective view of a fragment of the die; Fig. 3 is a section of one of the perforating elements; Fig. 4 is a perspective view of an embossed blank; Fig. 5 is a section of one of the impressing or embossing elements.

25 Fig. 1 illustrates a die for cutting toe tip blanks, and is provided with a tip perforating device constructed in accordance with the present invention. The die 12 is of the usual construction and comprises a continuous or endless frame of strip steel bent to the required outline and having one edge ground sharp for cutting and the other edge flattened to receive the pressure of the clicking press. On the inside of the 30 rear or straighter blade is adjustably secured an undercut bar or web 14 upon which are removably mounted blocks 24 carrying hollow punches 45 for perforating, or solid punches 25 for embossing the blank 35 cut by the die. The bar 14 is adjustable to and from the blade of the die by means of screws 18 and set screws 16, whereby the line of ornamentation may be located nearer or farther from the edge of the blank according to the space required by the stitching. At one end of the bar 14 is a stop 20 and at the other a detachable stop block 30 adapted to be secured to the bar by means of the screw 31 and provided with screws 50 22 for clamping the blocks 24—26 together and against the stop 20.

The blocks 24 are rabbeted at 37 to correspond with the bar 14 and slotted at 29. For forming perforations, hollow punches 55 45 are mounted in the blocks, as shown in Fig. 3, the blocks being perforated at 47 to allow the punchings to pass up into the slots 29, which in the assembled device constitute a continuous channel where the 60 punchings are retained and prevented from falling upon and obscuring the leather. The location of the bar 14 is such that the upper surface of each block 24 lies flush with the pressure receiving edge of the die so that 65 the working pressure is transmitted to each

of the punches independently of the die, thus relieving the die of any twisting stress when in use.

The punches may be of any desired shape, such as square, oval or circular and their arrangement on the blocks may be varied to form certain designs, for example, two or more punches may be mounted in a single block, as shown in Fig. 1.

Besides the punch-carrying blocks 24 there are provided spacing blocks 26, rabbeted and slotted like the former, said spacing blocks being for the purpose of separating the punch-carrying blocks on the bar 14 when it is desired to increase the distance 80 between two impressions or perforations forming part of the design.

As already stated it is desirable in some cases to emboss the design instead of forming it of perforations and for such work 85 there are provided blocks carrying solid punches 25 as shown in Fig. 5. These punches may be threaded into the blocks and furnished with a set nut 27 to prevent their working loose. The length of the solid 90 punches is less than that of the hollow punches in order that the design may be impressed into the blank but not punched out from it.

Fig. 4 illustrates a tip blank 40 cut out by 95 the die 12, the ornamentation 42 on the blank having been formed by solid embossing punches, similar to the punch 25 shown in Fig. 5. The ornamentation, therefore, in this case consists of a series of differently 100 shaped depressions formed in the surface of the blank.

The blank ornamenting devices hereinbefore mentioned have been described in detail and illustrated in connection with a tip 105 cutting die but it will be obvious that the invention is in no sense limited to this particular die but that devices embodying the invention may be advantageously used with dies for cutting foxings or quarters, or in 110 short, wherever it is desirable to employ a blank ornamenting or perforating device.

Having disclosed the nature of my invention and described several embodiments thereof, what I claim as new and desire to 115 secure by Letters Patent of the United States is:

1. A die for dying out tip blanks from upper leather comprising an open shallow frame having oppositely disposed pressure 120 receiving and cutting edges, in combination with means for perforating the blanks, comprising an undercut bar attached to the die, and a plurality of sections each provided with a device for forming on a blank, portions of a design, said sections being slotted to co-operate with said undercut bar and being interchangeable, whereby the design may be varied.

2. In a device of the class described, the 130

- combination with a die comprising an open frame having oppositely disposed pressure receiving and cutting edges, of a plurality of blank ornamenting elements each having 5 a pressure receiving surface, and a common supporting member for maintaining all said elements with their pressure receiving surfaces flush with the pressure receiving edge of the die.
10. 3. In a device of the class described, the combination with a die comprising an open frame having oppositely disposed pressure receiving and cutting edges, of a plurality of interchangeable blank ornamenting elements, and means for maintaining said elements in a line parallel to the cutting edge of said die and in position to be forced into the work by the direct action of a presser member.
20. 4. In a device of the class described, the combination with a die comprising an open frame having oppositely disposed pressure receiving and cutting edges, of a retaining member mounted on said die and a plurality 25 of blank ornamenting elements shaped to engage said retaining member, said ornamenting elements each having a pressure receiving surface adapted to be directly engaged by a presser member and co-operating 30 to impress the blank with an ornamental design.
5. A device of the class described, comprising a die for cutting blanks from sheet material, and a supplementary member for 35 ornamenting the blanks, comprising a bar and a plurality of slotted punch-carrying blocks interchangeably mounted thereon.
6. In a device of the class described, the combination with a die comprising an open 40 frame having oppositely disposed pressure receiving and cutting edges, of a supplementary member for ornamenting the blanks cut by the die, comprising a bar and slotted punch-carrying blocks and spacing blocks 45 interchangeably mounted thereon.
7. In a device of the class described, the combination with a die having continuous marginal pressure receiving and cutting edges, of a supplementary member for ornamenting the blanks cut by the die comprising interchangeable sections, and supporting means therefor interposed between said sections and the die.
8. In a device of the class described, the 55 combination with a die having continuous marginal pressure receiving and cutting edges, of punches for operating on the blank cut by the die and provision permitting movement of said punches in a direction parallel with a part of the cutting edge of 60 the die.
9. In a device of the class described, the combination with a die comprising an endless cutting blade, of a carrier member adjustably secured to part of said endless blade 65 and punches connected with said adjustable carrier and being themselves adjustable upon it and arranged for operating on the blank cut by the die.
10. In a device of the class described, the 70 combination with a die comprising an open frame having an endless cutting edge, of an intermediate member projecting from one side of said frame and punches attached thereto upon the side opposite to the frame 75 and arranged for operating on the blank cut by the die.
11. In a device of the class described, the combination with a die comprising an endless cutting blade, of a web projecting from 80 part of said blade, punches mounted thereon for sliding movement, and means for forcing the punches into position longitudinally of the web.
12. In a device of the class described, the 85 combination with a die comprising an endless cutting blade, of a web projecting from part of said blade, blocks slidably mounted thereon, punches carried by said blocks, and means for forcing the punch carrying blocks 90 into position on the web.
13. In a device of the class described, the combination with a die comprising an endless cutting blade, of a web projecting from part of said blade, a line of punches 95 mounted thereon for sliding movement, intermediate spacing blocks, and locking means for the punches and spacing blocks.
14. In a device of the class described, the combination with a die having a longitudinally extending slot formed in one side, 100 a bar retained in said slot and blank ornamenting members removably and interchangeably mounted on said bar.
15. In a device of the class described, the 105 combination with a die having a slot formed in one side, a bar maintained in said slot, means for adjusting the position of said bar relative to the side of the die and punches mounted on said bar.
- 110 In testimony whereof I have signed my name to this specification in the presence of two subscribing witnesses.
